UNITED STATES PATENT OFFICE

2,033,245

MACHINE FOR USE IN THE MANUFACTURE
OF SHOES

Bernhardt Jorgensen, Beverly, Mass., assignor to
United Shoe Machinery Corporation, Paterson,
N. J., a corporation of New Jersey

Application May 2, 1934, Serial No. 723,567

40 Claims. (Cl. 12—7)

This invention relates to machines for use in the manufacture of shoes and is herein illustrated as embodied in a machine for use in assembling the upper of a tennis shoe or sneaker on its last and for securing the upper to an insole on the last preparatory to the lasting of the upper by means of a machine such, for example, as that disclosed in United States Letters Patent No. 1,843,232, granted February 2, 1932, upon application of the present inventor.

In the manufacture of tennis shoes it has been the practice for the lasting machine operator, after having mounted a last, having an upper loosely assembled thereon, upon the spindle of the lasting machine and before starting the machine, to pull the upper forwardly by his fingers so as to draw it closely about the heel portion of the last, and also to pull the opposite side portions of the upper upwardly by his fingers, to draw the upper closely about the forepart of the last, and finally to place an insole in proper position upon the last bottom.

One object of the present invention is to provide a machine which is well adapted for performing such preparatory operations as those above referred to so that the operator of the lasting machine will be relieved of the necessity of performing them manually before starting the lasting machine and which can be relied upon to operate rapidly and effectively and to insure accuracy and substantial uniformity of adjustment of the uppers on the lasts.

With this and other objects in view, one feature of the invention consists in the provision, in an assembling machine, of means for drawing an upper tightly about the heel end of a last by a pull applied at the forepart, and means for drawing the upper tightly across the forepart of the last and for securing its margin adhesively to an insole on the last at the sides of the forepart only while leaving the upper around the end of the toe unsecured. In the machine herein illustrated a last having an insole and an upper loosely mounted thereon is supported bottom downward by means of a work support which comprises a toe rest and a heel rest arranged to engage the toe and heel portions, respectively, of the insole. As shown, a toe gage and two side gages are associated with the toe rest for positioning the insole with the edge of its forepart alined with the corresponding edge of the last bottom and for positioning the last with the upper and the insole in position to be operated upon, the gages being arranged to extend between the upper and the last and to engage the

edge of the insole and the edge of the last bottom, and the toe gage serving also to hold the last against forward displacement during the action of the operating parts of the machine. These operating parts, as herein shown, comprise a foredraw member, two side wipers, and two overlaying devices all of which are normally retracted from work-engaging positions to facilitate introduction and removal of the work. In the illustrated machine treadle-operated mechanism is provided for moving the foredraw member into engagement with the upper at a point above the toe of the last and for yieldingly pressing it toward the last to cooperate with the toe rest in clamping the last, and power means rendered operative by movement of the above-mentioned treadle thereafter moves the foredraw member in a direction to draw the upper forwardly and thereby to tighten it about the heel of the last while at the same time continuing to exert clamping pressure upon the last. As illustrated, the side wipers are brought into yielding frictional engagement with the upper at the opposite sides of the toe of the last and moved downwardly to tighten the upper widthwise of the last, these wipers being brought to rest near the bottom edge of the last where they function to hold the upper in its tightened condition while the cemented margins of the upper are pressed against and caused to adhere to the bottom face of the insole by the action of the overlaying devices. As shown, the overlaying devices comprise rolls which are moved inwardly to lay the cemented margins of the upper over the insole and are arranged to exert yielding pressure to secure the margins adhesively to the insole so that the upper will be held in its adjusted and tightened condition while the work is being transferred to the lasting machine.

The invention further consists in features of construction and combinations and arrangements of parts hereinafter described and claimed the advantages of which will be apparent to those skilled in the art.

The invention will be explained with reference to the accompanying drawings in which

Fig. 1 is a view in right-hand end elevation of an assembling machine embodying the features of the present invention, the assembling machine being shown as attached to the rear of a lasting machine such as that disclosed in the above-mentioned Letters Patent No. 1,843,232;

Fig. 2 is a view partially in left-hand side elevation and partially in section of the assembling machine showing a last having an upper and an

insole loosely assembled thereon in position to be operated upon, the machine being shown detached from the lasting machine and tilted approximately forty-five degrees from the position shown in Fig. 1;

Fig. 3 is a view partially in rear elevation and partially in section along the line III—III of Fig. 2;

Fig. 4 is a top plan view of the assembling machine showing the machine positioned as in Fig. 2, parts of the machine being broken away and a cover plate being removed from the casing to reveal portions of the mechanism which otherwise would be concealed from view;

Fig. 5 is a vertical sectional view of a portion of the assembling machine, the section being taken along a central longitudinal plane;

Figs. 6 and 7 are fragmentary views partially in rear elevation and partially in section of the parts shown in Fig. 3, but showing those parts in different operative positions; and

Fig. 8 is a perspective view showing an upper and an insole assembled on a last and illustrating particularly the appearance of the upper after it has been operated upon by the assembling machine.

In the drawings, the invention is illustrated as embodied in an assembling machine which is particularly designed for attachment to a lasting machine of a type especially adapted for use in the lasting of tennis shoes or the like in which the uppers are fastened to the insoles by cement, such a lasting machine being shown at 10 in Fig. 1 and being of the same general character as that disclosed and claimed in Letters Patent No. 1,843,232, hereinbefore referred to. Reference may be had to said Letters Patent if desired for a description of the construction and mode of operation of the lasting machine, although for the purpose of an understanding of the present invention it will be necessary only to know that a conveyor belt 12 is provided for carrying shoes away from the vicinity of the lasting machine after they have been operated upon and that the conveyor belt is operated through worm gearing 14 from a shaft 16 which is driven through sprocket wheels and a chain 18 by a shaft 20 having on one end a beveled pinion 22 operated by a bevel gear 24 secured to one side of a gear wheel 26 which is continuously running while the lasting machine is in operation.

The illustrated assembling machine comprises a casing 30 on the outside of which the operating instrumentalities of the machine are mounted, the casing 30 being rigidly secured by means of screws 32 and a tie bolt 34 to the rear of the lasting machine 10. Located above the casing 30 and supported thereby is a heel rest 36 and a toe rest 38 (Fig. 2) for the heel and toe portions, respectively, of a last, such as the last A, having an upper B and an insole C arranged in loose relation thereon. In Fig. 2, for convenience of illustration, the casing 30 is shown in such a position that the supporting surfaces of the heel rest 36 and the toe rest 38 are horizontal but actually the casing 30 is so positioned relatively to the lasting machine 10, as shown clearly in Fig. 1, that the heel and toe rests are inclined lengthwise of the shoe so that the toe end of the shoe points upwardly and thus the operator of the assembling machine, without having to bend forwardly or assume an unnatural position, may look downwardly upon the loosely assembled upper so as conveniently to observe the condition of the upper as it is being operated upon by the instrumen-

talities of the machine. Associated with the toe rest 38 are side gages 40 and a toe gage and abutment 42 which relatively locate the foreparts of the insole and the last and which locate and hold the last, with the loosely assembled upper and insole thereon, in position to be operated upon. The operating instrumentalities of the assembling machine are arranged higher than the casing 30 at the rear thereof and comprise a foredraw member 46 for frictionally engaging the top of the forepart of the upper and drawing the latter forwardly to tighten it about the heel portion of the last, two side wipers 48 for wiping the forepart of the upper downwardly over the opposite sides of the last, and two overlaying devices 50 for pressing the lower cemented margins of the upper upon the insole for the purpose of securing them thereto.

The foredraw member 46 is adapted to be moved into frictional engagement with the upper on the last by depression of a foot treadle 52 (Fig. 1). Continued downward movement of the treadle 52 initiates the operation of the foredraw member 46, the side wipers 48 and the overlaying devices 50 under power, the power being transmitted by sprocket wheels and a chain 54 from the driven shaft 16 to a cam shaft 56 which is journaled in bearings in the side of the casing 30 and which carries a plurality of cams and also a clutch 58 of suitable well-known form, the latter being connected with the treadle 52 by means of a treadle rod 60 and being operable to cause the cam shaft 56 to make a single revolution and then automatically come to rest.

The heel rest 36 comprises a flat plate arranged to engage the insole beneath the heel end of the last. As best shown in Fig. 2, the heel rest plate 36 is provided with a cylindrical stem 62 which extends through and is arranged for lengthwise sliding adjustment in vertical bearings 64 one of which is formed in a plate 66 which constitutes a cover for the casing 30 and the other of which is formed in a bracket 68 which is rigidly secured to the upper side of the cover plate 66. The heel rest stem 62 is externally threaded to receive a knurled nut 70 which is located between a portion of the bracket 68 and the cover plate 66 and is adapted to be turned to raise or lower the heel rest to accommodate lasts the bottoms of which have different degrees of slope in their shank portions. To prevent the stem 62 from turning in its bearings and thereby enabling it to be adjusted vertically by the turning of the nut 70, a key 72 in the bracket 68 is received within a vertically elongated keyway 74 in the stem 62.

The illustrated toe rest 38 comprises a flat plate which is adjustably mounted upon a stationary bracket 80 which projects from the side of the casing 30, the toe rest plate 38 being arranged to support the last by engagement with the bottom face of the insole at the extreme forward or toe portion of the latter. The toe rest 38 is of small area, as shown in Fig. 4, and is arranged with its lateral edges spaced inwardly substantial distances from the edges of the insole and the last bottom so as not to interfere with the movements of the overlaying devices 50 in pressing the margins of the upper against the insole. As shown, the toe rest 38 has formed at its forward extremity an integral upstanding lug 42 arranged to engage the toe end of the insole and to project upwardly beyond the insole so as to engage also the toe end of the last. The lug 42 thus constitutes a fixed abutment for holding the last against the forward thrust of the foredraw member 46 so as

positively to prevent any forward lengthwise displacement of the last resulting from the action of the foredraw member. The lug 42 functions also as a gage to locate the last, with the upper thereon, in the desired lengthwise relation to the operating instrumentalities of the machine and to aline the edge of the insole with the edge of the last bottom at the tip of the toe. In order that the toe gage and abutment 42 may be adjusted to accommodate lasts of different sizes and styles, a rib 82 (Figs. 3 and 5) formed on the lower side of the toe rest plate 38 is dovetailed for sliding adjustment in directions toward and from the heel rest 36 in a slideway 84 formed in the upper portion of the bracket 80 and a hand screw 86 is provided for effecting such adjustment. As shown, the hand screw 86 extends into a bore in the rib 82 on the toe rest 38, the threads on the screw engaging screw threads formed within the bore while at its opposite end, the screw 86 extends through and is arranged to turn freely within a bearing lug 88 on the bracket 80. The screw 86 is held against longitudinal movement in its bearing in the lug 88 by means of a collar 89 on the screw, arranged to engage one end of the bearing lug 88, and a knurled head 90 which is arranged to engage the opposite end of the bearing lug and by means of which the screw 86 may conveniently be turned for the purpose of adjusting the toe rest 38 and the toe gage and abutment 42.

The side gages 40 function to aline the lateral edges of the insole with the corresponding edges of the last bottom at the forepart of the last and, in addition, to locate the last, with the upper and insole loosely assembled thereon, in a central position relatively to the side wipers 48 and the overlaying devices 50. As a result of this arrangement the side wipers will so act upon the opposite sides of the upper in conforming the upper to the curve of the last as to insure against any tendency of the upper to slip sidewise in such a manner as to displace the throat opening in the upper from the desired central position on the last or to cause the tip line D of the upper to be improperly positioned. This arrangement further insures that the overlaying devices shall operate with the best results in securing the margins of the upper to the insole.

As shown in Fig. 3, the side gages 40 comprise vertically disposed fingers the lower ends of which are pivoted at 92 to ears 93 on a slide 94 which is movable in a vertical slideway comprising guiding faces formed at the inner sides of parallel flanges 95 on the casing 39 so that the side gages, after having performed their locating functions, may be lowered out of the way of the side wipers 48 and the overlaying devices 50 to avoid interference with the latter as will be hereinafter explained. The illustrated gage fingers 40 are formed at their upper ends with substantially horizontal faces 96 for engagement with the opposite marginal portions of the lower surface of the insole to cooperate with the toe rest 38 in supporting the insole and the last, and with upstanding lugs 98 (best shown in Fig. 3) for engagement with the opposite edges of the insole substantially in the plane of the tip line of the upper, if the upper has a toe tip, and for over-lapping the adjacent edge portions of the sides of the last. These side gage lugs 98 function relatively to position transversely the forepart of the insole and the forepart of the last. The side gage fingers 40 are adjustable toward and from each other to accommodate insoles and lasts of differ-

ent widths and means is provided for adjusting the gage fingers, this means comprising two manually operable bell-crank levers 100 (see Fig. 4) which are pivoted at 102 to a portion of the casing 30 and are arranged with the free ends of their longer arms extending between and operatively engaging the gage fingers. As shown, the gage fingers 40 are held yieldingly against the arms of the bell-crank levers 100 by means of springs 104 (Fig. 3) acting upon extensions 106 of the gage fingers. The shorter arms 108 of the bell-crank levers 100 extend toward each other and are formed at their ends with gear segments 110 the teeth of which intermesh, the arrangement being such as to maintain the levers 100 with the ends of their long arms equidistant from a vertical plane which is centrally disposed relatively to the side wipers 48 and the overlaying devices 50, and consequently to maintain the side gage fingers 40 in a similar relation to that plane so as to insure uniformity of action of the side wipers 48 and overlaying devices 50 upon opposite sides of the upper. For the purpose of operating the bell-crank levers 100 to adjust the side gage fingers 40 toward or from each other an adjusting screw 112 is provided, the screw 112 extending through and having threaded engagement with blocks 114 (see Fig. 5) which are swiveled upon the long arms of the levers 100, the pitch of the threads cooperating with one of the blocks 114 being opposite to the pitch of the threads cooperating with the other block so that turning of the screw 112 in one direction will result in moving the levers 100, and consequently the gage fingers 40, simultaneously in opposite directions. The screw 112 extends outwardly through an opening in the casing 30 and is provided, outside of the casing, with a knurled head 116 by means of which the screw may be turned to effect a desired adjustment of the gage fingers 40.

It will be seen from the foregoing that a last having an upper and an insole loosely assembled therewith is supported, while the upper is being operated upon in this machine, by means of the heel rest 36 and the toe rest 38 and that the horizontal faces 96 on the side gage fingers 40 assist in supporting the forepart of the last until they are lowered to make way for the side wipers 48 and the overlaying devices 50. It will also be seen that the forepart of the insole is located with its edge registering with the edge of the last bottom by means of the side gages 40 and the toe gage 42, that the last with the upper and the insole thereon is located lengthwise with respect to the operating instrumentalities by means of the toe gage 42, and that the last is located widthwise in position for the upper to be operated upon by means of the side gages 40. Moreover, the side gages 40, whatever their positions of adjustment, are located equidistant from a vertical plane centrally disposed with respect to the foredraw member 46 so as to insure that the foredraw member will act upon the central portion of the upper as well as to insure substantial uniformity of action of the side wipers and the overlaying devices upon opposite sides of the upper.

The foredraw member 46 (as best shown in Figs. 2 and 5) consists of a lever which is fulcrumed upon a horizontal pin 120 that is located somewhat below and forwardly of the toe of a last supported by the heel rest 36 and the toe rest 38. The foredraw lever 46 is curved upwardly and forwardly from its fulcrum pin 120 to overlie the toe of the last and its upper free extremity is provided with a pad 122 of soft rubber.

or other yieldable material adapted to conform readily to the curvature of the last when pressed against the latter so as to secure firm frictional engagement with the upper without having any tendency to injure the latter. When the machine is idle the foredraw lever 46 is elevated somewhat above the position in which it appears in Fig. 2 to facilitate the placing of the last in position upon the toe rest 38. The lever 46 is swung 10 downwardly by means of the foot treadle 52 to bring the pad 122 into the position shown in Fig. 2 for engagement with the upper, and thereafter the fulcrum pin 120 is moved by power in a direction lengthwise of the last to move the lever 46 15 bodily forward for the purpose of foredrawing the upper and tightening it about the heel of the last. To permit the fulcrum pin 120 to be moved as just described it is supported by a yoke 124 which embraces the lever and is carried at 20 the forward end of a plunger 126 which extends through and is adapted to slide within a horizontal bore in the bracket 80, the plunger being acted upon by a spring 128 tending to move it in a direction to hold a shoulder 130 on the yoke 124 25 seated against the outer end of the bracket 80. As shown, the spring 128 is connected at one end to the plunger 126 and at its opposite end to an adjusting screw 132 which extends through an aperture in the casing 30 and is provided outside 30 of the casing with a wing nut 134 which may be turned to vary the tension of the spring. For the purpose of swinging the foredraw lever 146 about its fulcrum pin 120 into and out of engagement with the work and moving the lever 46 bodily to draw the upper forwardly on the last the lower arm 136 of the lever 46 is connected by a rod 138 with the upwardly extending arm 140 of a three-arm lever which is pivotally mounted upon a fixed horizontal rod 142, the three-arm lever having a downwardly extending arm 144 which carries a cam roll 146 arranged 35 to engage the periphery of a cam 148 on the cam shaft 56 and a second downwardly extending arm 150 which is connected by means of a rod 152 with the foot treadle 52. A spring 154 secured 40 at its upper end to the casing 30 and at its lower end to the rod 152 tends to turn the three-arm lever 140, 144, 150 in a direction to hold the cam roll 146 in engagement with the cam 148, and to 45 hold the foredraw lever in its normal elevated position. Upon depression of the treadle 52 the roll 146 is carried away from the cam 148 and the foredraw lever is swung downwardly to press the pad 122 into firm frictional engagement with 50 the upper, after which continued downward movement of the treadle 52 will operate, through the treadle rod 60, to throw the clutch 58 and thus to start the operation of the machine under power. During the operation of the machine 55 under power the roll 146 is engaged by the cam 148 and the foredraw member 46 is operated to tighten the upper upon the last.

As shown, the treadle rod 60 is connected at its upper end with a clutch-controlling lever 158 60 which is pivoted at 160, the upper portion of the rod 60 having a pin-and-slot connection 162 with the lever 158 arranged to permit the rod 60 to move downwardly without moving the clutch-controlling lever 158 until after the foredraw pad 122 65 has engaged the upper. The clutch 58 is a clutch of the Horton type which is so well known that it need not be particularly described. It will be understood, however, that this clutch has friction rollers adapted rotatably to connect its two 70 elements of which the outer element 164 (Fig. 1) 75

is pinned to the cam shaft 56 while the inner element 166 is fixed to a sprocket wheel 168 that is carried by the cam shaft 56 and over which passes the sprocket chain 54. The friction rollers of the clutch 58 are normally held out of operation by means comprising a controller ring 170 (Fig. 2) provided with a shoulder 172 arranged to cooperate with the hooked extremity of the clutch controlling lever 158. The clutch-controlling lever 158 is held in operative position by means of a spring (not shown). When the lever 158 is momentarily disengaged from the controller ring 170 by depression of the foot treadle 52 the clutch 58 operates to impart a single rotation to the cam shaft 56 and the cams thereon 10 and is then arrested by engagement of the lever 158 with the shoulder 172. As soon as the clutch is thrown into operation the cam 148 moves the three-arm lever 140, 144, 150 in a counterclockwise direction and, through the rod 138, moves 15 the foredraw lever 46 bodily toward the left, the plunger 126 sliding outwardly against the tension of the spring 128 to permit such movement of the lever 46 to take place. During this bodily movement of the lever the latter is constantly urged about its fulcrum 120 in a direction such 20 that the foredraw pad 122 is continually held in firm frictional engagement with the upper. 25

The side wipers 48 comprise pads of soft rubber or the like which are secured to the inwardly turned upper ends of two levers 178 arranged one at either side of the forepart of the last so that the pads will engage the upper approximately in the plane of the tip line, the levers 178 having inwardly turned lower extremities which 30 are pivoted at 180 to ears 182 which project in opposite directions from a slide 184 that is mounted below the slide 94 for up-and-down movement in the guideway formed by the vertical guiding faces 95 already referred to. Substantially midway between the upper and lower ends of the levers 178 these levers are connected together by means of a spring 186 which tends to swing the levers toward each other, the inward movements of the levers under the influence of the spring 35 being limited by engagement of rolls 188 carried by the levers with inclined cam faces 190 formed on plates 192 which are rigidly secured by means of screws 194 to the outside of the casing 30. The slide 184 is connected by means of a link 196 with the upper end of a cam lever 198 (Fig. 2) which is pivotally mounted upon the rod 142 and which carries at its lower end a cam roll 200 arranged to engage the periphery of a cam 202 on the cam shaft 56. A spring 204, connected with 40 the lever 198, tends to swing the lever in a direction to hold the slide 184 in its upper position and to hold the roll 200 against its cam. When the machine is idle the levers 178 occupy the positions shown in Fig. 3 with the side wipers 48 spaced upwardly and outwardly with respect 45 to the upper on the last. Upon rotation of the cam shaft 56 the cam 202 operates to rock the lever 198 in a direction to lower the slide 184 and to move the side wiper levers 178 downwardly. As the levers 178 move downwardly the spring 186 operates to swing the levers inwardly about their pivots 180 under the control of the cam faces 190 until the side wipers 48 engage the upper and are held in firm frictional engagement therewith by means of the spring 186. The cam faces 190 are designed to cause the side wipers 48 to engage the upper at points spaced 50 outwardly from the foredraw member 46 and as the levers 178 continue to move downwardly the 55 70 75

spring 186 yields to permit the side wipers to separate as required to follow the curved contour of the last while serving to maintain frictional engagement of the side wipers with the upper 5 so as to wipe the upper downwardly over the opposite sides of the toe portion of the last and thus to tension it transversely in the vicinity of the tip line.

As shown, the overlaying devices 50 are in the 10 form of rolls, the rolls being carried in the forked upper extremities of two plungers 206 which are guided for sliding movements in sockets 208 (Fig. 3) formed in the upper arms of two levers 210 which are mounted for swinging movements 15 toward and away from each other about fixed pivots 212. The lower portion of each plunger 206 is bored as indicated at 214 to receive a spring 216, the upper extremity of which bears against the upper end of the bore 214 and the 20 lower end of which is seated against the bottom of the socket 208. Upward movement of each plunger 206 in its socket 208 is limited by means of a stop screw 218 carried by the plunger and arranged to engage the lever 210 at the upper end 25 of a slot 220 in the lever. The levers 210 extend downwardly below their pivots 212 and are connected together at their lower ends by means of two toggle links 222 and 224, the outer ends of which are pivoted at 226 to the levers 210 and 30 the inner ends of which are pivotally connected with each other by means of a screw 228 which serves also to secure the toggle links pivotally to the slide 94 which also carries the side gage fingers 40. The slide 94 is connected by means 35 of a link 230 (Fig. 2) with one arm of a lever 232 that is mounted to turn on the rod 142, and the other arm 234 of which carries a cam roll 236 arranged to bear upon the periphery of a cam 238 on the cam shaft 58. A spring 240 (Fig. 4) connected with the lever arm 232 tends to hold the slide 94 in its uppermost position and to hold the roll 236 against its cam. The cam 238 operates to lower the slide 94 and to straighten the 40 toggle 222, 224, the straightening of the toggle 45 moving the overlaying devices inwardly to press the margins of the upper against the insole and the lowering of the slide 94 withdrawing the side gages 40 from the paths of the side wipers 48 and the overlaying devices 50.

To prepare the upper of a tennis shoe or sneaker to be operated upon by the lasting machine 10 the operator of the above described assembling machine, after having first placed an upper and an insole in loosely assembled relation 50 upon a last, presents the last and the parts thereon right side up to the assembling machine, positioning the last so that the toe and heel portions of the insole rest upon the toe rest 38 and the heel rest 36, respectively, with the toe of the 55 last beneath the foredraw member 122 (which is elevated somewhat above its work-engaging position) and thrusting the last forwardly to engage the edge of the insole and the edge of the last bottom with the toe gage 42 and with the 60 side gages 40. It will be understood that the heel rest 36 has been previously adjusted vertically by manipulation of the nut 70 into position to cooperate properly with the toe rest 38 in supporting the last and that the gages 40 and 42 have 65 been adjusted by means of the screws 112 and 86, respectively, as may have been required in accordance with the size and style of the particular last being operated upon. It should also be understood that the lower margin of the upper 70 has previously been coated on its inner side with

cement which will cause the upper to become firmly secured to the insole when pressed against the insole by the overlaying rolls 50. The gages 40 and 42 project upwardly between the upper and the sides of the last, the toe gage 42 functioning to align the edges of the insole with the edge of the last bottom at the tip of the toe and to locate the last and the parts thereon lengthwise in position to be operated upon, while the side gages 40 align the opposite lateral edges of 10 the insole and the last bottom at the forepart of the last and serve to locate the forward portions of the last, the upper, and the insole widthwise in proper relation to the operating instrumentalities of the assembling machine. 15

The work having been presented to the assembling machine and positioned thereon as above described, the operator depresses the foot treadle 52, thereby causing the foredraw lever 46 to be rocked by foot power about its pivot 20 120 to lower the pad 122 into frictional engagement with the upper, in which position the member 122 cooperates with the toe rest 38 in clamping the work so as to prevent the last and the insole from being displaced while the upper is 25 being operated upon. The shoulders 96 on the side gage fingers 40 also cooperate with the pad 122 in the initial clamping of the work. As the treadle 52 is moved further downward by the operator the clutch 58 is tripped and the machine 30 starts to operate under power. At the beginning of its cycle of operations under power the mechanism operated by the cam 148 functions to move the pivot 120 of the foredraw lever 46 forwardly relatively to the last, while at the same time exerting a force tending to rock the lever 46 about its pivot 120 so as to maintain the pad 122 in effective holding engagement with the upper. As the downward pressure on the pad 122 is maintained and as the pad 122 moves forwardly of the 35 last under power as a result of the forward movement of the pivot 120, the upper is drawn forwardly toward the toe of the last and is thus tightened about the heel end and along the sides of the last. During the above foredraw movement of the member 122 the mechanism operated by the cam 202 lowers the side wipers 48, the spring 186 moving the side wipers inwardly, under the control of the cam faces 190, into yielding frictional engagement with the upper at opposite 40 sides of the foredraw lever 46, and causing the wipers yieldingly to wipe the upper downwardly over the forepart of the last to tension it widthwise of the last, and finally holding the side wipers pressed against the upper in the positions in which they appear in Fig. 6 to maintain the upper in tensioned condition during the laying of its lower marginal portions over the insole. During the downward movements of the side wipers 48 the mechanism actuated by the cam 45 238 starts to straighten the toggle 222, 224, thereby moving the overlaying rolls 50 toward each other and at the same time lowering the slide 94 and the side gages 40. The side gages 40 are lowered to positions sufficiently below the insole 50 to avoid interference with the operative movements of the side wipers and the overlaying rolls. The overlaying rolls engage the downwardly projecting margins of the upper and, after the side wipers have completed their downward wiping 55 movements, the overlaying rolls move inwardly to the positions shown in Fig. 7, during which movements they lay the upper margins against the lower face of the insole and press them firmly against the insole so that the portions of the 60 70 75

upper margins engaged by the rolls will be secured to the insole by means of the cement on the inner sides of the margins of the upper. Thus the upper is securely held in its tensioned condition upon the last so that it will not become displaced during the transfer of the last to the lasting machine. During the latter part of the cycle of operations of the assembling machine the operative parts of the machine are returned to their starting positions to facilitate the removal of the work which has been acted upon and permit the presentation of a new piece of work to the machine. The foot treadle having been released by the operator shortly after the starting of the cycle of operations, the clutch lever 156 is returned into position to function, after the cam shaft 58 has completed a single revolution, to stop the machine with the operative parts in the positions shown in Fig. 1 ready for the performance of another assembling operation.

Having described the invention, what I claim as new and desire to secure by Letters Patent of the United States is:

1. In an assembling machine, means for drawing an upper tightly about the heel end of a last by a pull applied at the forepart, and means for drawing the upper tightly across the forepart of the last and for securing its margin adhesively to an insole on the last at the sides of the forepart only while leaving the upper around the end of the toe unsecured.

2. In an assembling machine, means for drawing an upper tightly about a last lengthwise and laterally of the last by engaging it frictionally in locations opposite the top and the sides of the forepart of the last respectively, and means for laying the margin of the upper inwardly over an insole on the last and for securing it adhesively to the insole at the sides of the forepart only while leaving the upper around the end of the toe unsecured.

3. In an assembling machine, a pad arranged to engage an upper frictionally in a location opposite the top of the forepart of a last and to work the upper forwardly on the last by its frictional action on the upper, wipers arranged to engage the upper frictionally at the sides of the forepart of the last to tighten the upper across the forepart, and means for laying the margin of the upper inwardly over an insole on the last and for securing it to the insole adhesively at the sides of the forepart only while leaving the upper around the end of the toe unsecured.

4. In an assembling machine, gaging means for relatively positioning a last and a loose insole, and means for conforming the upper tightly to the last and for securing its margin adhesively to the insole at the sides of the forepart only while leaving the upper around the end of the toe unsecured.

5. In an assembling machine, gaging means for relatively positioning a last and a loose insole both lengthwise and widthwise of the forepart of the last, and means for conforming the upper tightly to the last and for securing it to the insole at the sides of the forepart only while leaving the upper around the end of the toe unsecured.

6. In a machine for shaping uppers over lasts, gaging means for relatively positioning a last and a loose insole both lengthwise and widthwise of the last by engagement with the last and the edge of the insole at the forepart, means for drawing an upper tightly about the last lengthwise and laterally of the last by engaging it frictionally in locations opposite the top and the sides of the

forepart of the last respectively, and means for laying the margin of the forepart of the upper inwardly over the insole and for securing it to the insole.

7. In a machine for shaping uppers over lasts, 5 work support arranged to receive and support a last with an upper mounted thereon when the operator presents the work initially to the machine, gaging means associated with said work support for relatively positioning the last and a loose insole by engagement with the forepart of the last and the edge of the insole, and means for conforming the upper to the last and for securing its margin adhesively to the insole.

8. In a machine for shaping uppers over lasts, 15 a work support arranged to receive and support a last positioned bottom downward and having an upper mounted thereon when the operator presents the work initially to the machine, means for drawing the upper tightly about the last lengthwise and laterally of the last by engaging it frictionally in locations opposite the top and the sides of the forepart of the last respectively, and means for laying the margin of the upper inwardly over an insole on the last and for securing it adhesively 20 to the insole.

9. In a machine for shaping uppers over lasts, 25 a member movable into engagement with an upper in a location opposite the top of the forepart of a last and movable lengthwise of the last to work the upper forwardly on the last, and wiping members arranged to engage the upper frictionally in locations opposite the sides of the forepart of the last and to draw the upper tightly across the forepart by relative movement of the last and said 30 members heightwise of the last.

10. In a machine for shaping uppers over lasts, 35 a member movable into engagement with an upper in a location opposite the top of the forepart of a last and movable lengthwise of the last to work the upper forwardly on the last, and wiping members movable widthwise of the last into positions to engage the upper frictionally at the opposite sides of the forepart and movable heightwise of the last to draw the upper tightly across the forepart of the last.

11. In a machine for shaping uppers over lasts, 40 members arranged to engage an upper frictionally in locations opposite the sides of the forepart of a last and movable heightwise of the last in wiping contact with the upper to draw the upper tightly across the forepart of the last, and rolls movable to lay the margin of the upper inwardly over an insole on the last at the sides of the forepart.

12. In a machine for shaping uppers over lasts, 45 a member arranged to engage an upper frictionally in a location opposite the top of the forepart of a last, a lever fulcrumed between its opposite ends and having said member mounted on one 50 arm thereof, a support on which said lever is fulcrumed, said support being movable with the lever in directions lengthwise of the last, and means arranged to act on the other arm of said lever to swing said member into engagement with the 55 upper and then to move said lever and its support lengthwise of the last to cause said member to work the upper forwardly on the last.

13. In a machine for shaping uppers over lasts, 60 a member arranged to engage an upper frictionally in a location opposite the top of the forepart of a last, a lever fulcrumed between its opposite ends and having said member mounted on one arm thereof, a support on which said lever is 65 fulcrumed, said support being movable with the 70

- lever in directions lengthwise of the last, mechanism movable by the operator and arranged to act on the other arm of said lever to swing said member into engagement with the upper, and power-operated means arranged to act thereafter through said mechanism to move said lever and its support lengthwise of the last and thus to cause said member to work the upper forwardly on the last.
14. In a machine for shaping uppers over lasts, a member arranged to engage an upper frictionally in a location opposite the top of the forepart of a last, power-driven means for moving said member lengthwise of the last to cause it to work the upper forwardly of the last, and a member movable by the operator to force said upper-engaging member into contact with the upper and further movable to start said power-driven means in operation.
15. In a machine for shaping uppers over lasts, a member arranged to engage an upper frictionally in a location opposite the top of the forepart of a last, a lever supporting said member and mounted for swinging movement, a support for said lever movable in directions lengthwise of the last, power-driven means for moving said support and lever lengthwise of the last to cause said member to work the upper forwardly on the last, and a member movable by the operator to swing said lever and force said upper-engaging member into contact with the upper and further movable to start said power-driven means in operation.
16. In a machine for shaping uppers over lasts, a member arranged to engage an upper frictionally in a location opposite the top of the forepart of a last, said member being movable by the operator into upper-engaging position, and power-operated means for thereafter moving said member lengthwise of the last to work the upper forwardly on the last.
17. In a machine for shaping uppers over lasts, members arranged to engage an upper frictionally in locations opposite the sides of a last, means for effecting relative movement of said members and the last heightwise of the last to cause them to tighten the upper over the last by their wiping action thereon, spring means tending to move said members toward each other widthwise of the last, and cam means controlling said members and arranged to permit them to be moved toward each other by said spring means in the course of the relative movement of the members and the last heightwise of the last.
18. In a machine for shaping uppers over lasts, members arranged to engage an upper frictionally in locations opposite the sides of a last, means for moving said members heightwise of the last to cause them to tighten the upper over the last by their wiping action thereon, spring means tending to move said members toward each other widthwise of the last, and stationary cams controlling said members and arranged to permit them to be moved toward each other by said spring means as they are moved heightwise of the last.
19. In a machine for shaping uppers over lasts, members mounted for swinging movements widthwise of a last to lay the margin of an upper inwardly over the bottom of the last at the opposite sides thereof, and a toggle connecting said members and arranged to be straightened to move the members inwardly over the bottom of the last.
20. In a machine for shaping uppers over lasts,
- rolls for laying the margin of an upper inwardly over the bottom of a last at the opposite sides of the last, arms supporting said rolls and mounted for swinging movements to carry the rolls inwardly over the last bottom, and a toggle connecting said arms together and arranged to be straightened to operate them, said rolls being yieldable heightwise of the last relatively to the arms.
21. In a machine for shaping uppers over lasts, a support for a last having an upper loosely mounted thereon, a member for engaging the toe of the upper, means for moving said member first in one direction to cooperate with said support in holding the last and thereafter in another direction to draw the upper forwardly to tighten it on the heel of the last, and means for positioning the toe of the last lengthwise and widthwise relatively to said member.
22. In a machine for shaping uppers over lasts, a support for the forepart of a last having an upper and an insole loosely disposed thereon, a carrier mounted for forward yielding movement relatively to the last, a foredraw lever pivoted to said carrier and provided with a pad for engaging the upper, mechanism movable by the operator for rocking said lever about its pivotal connection with said carrier to engage said pad with the upper, and power-operated means coacting with said mechanism for moving said lever forwardly relatively to the last to draw the upper forwardly so as to tighten it about the heel of the last.
23. In a machine for assembling an upper in tight fitting relation upon a last, a support for a last having an upper loosely mounted thereon, a member for clamping the last to said support and tightening the upper about the last, operator-actuated means for moving said member into clamping position, and power means for moving said member to tighten the upper about the last.
24. In a machine for assembling an upper in tight fitting relation upon a last, a support for a last having an upper loosely mounted thereon, a member for clamping the last to said support and tightening the upper about the last, means operated by a treadle for moving said member into last-clamping position, and power means rendered operative by further movement of said treadle for moving said member to tighten the upper about the last.
25. In a machine for use in assembling an upper on a last, a toe rest for supporting the toe of a last having an upper in loosely assembled relation thereon, means for wiping the upper over the sides of the forepart of the last to tighten the upper on the last, gages constructed and arranged to extend between the upper and the last at opposite sides of the last for positioning the last widthwise relatively to said wiping means, means for retracting said gages from between the upper and the last to make way for said wiping means, and means on said gages for cooperating with said toe rest in supporting the last.
26. In a machine for use in assembling an upper on a last, a rest constructed and arranged to afford support for the toe portion of a last, means for wiping an upper over the sides of the forepart of the last, gages arranged to engage the opposite sides of the last to position the last widthwise relatively to said wiping means, and means on said gages for supporting the last against the thrust of said wiping means, said gages being retractable from operative positions.

to facilitate operations upon the margin of the upper.

27. In a machine for assembling an upper in close fitting relation upon a last, means for supporting a last having an upper loosely assembled thereon, a foredraw member for drawing the upper forwardly to tighten it upon the heel portion of the last, side wipers for tensioning the upper widthwise upon the forepart of the last, and gages constructed and arranged to extend between the upper and the last and to engage the opposite sides of the forepart of the last to position the last widthwise relatively to the foredraw member and the side wipers.

15 28. In a machine for assembling an upper in close fitting relation upon a last, means for supporting a last having an upper loosely assembled thereon, a foredraw member for drawing the upper forwardly to tighten it upon the heel portion of the last, side wipers for tensioning the upper widthwise upon the forepart of the last, gages constructed and arranged to extend between the upper and the last and to engage the opposite sides of the forepart of the last to position the last widthwise relatively to the foredraw member and the side wipers, and means for retracting said gages from operative positions to facilitate the operation of the side wipers.

30 29. In a machine for use in assembling an upper on a last, a toe rest and a heel rest arranged to engage respectively the toe and heel portions of the bottom of an insole on a last having an upper assembled in loose relation thereon, said rests being relatively adjustable in directions heightwise and lengthwise of the last and being arranged to cooperate in supporting the last, a toe gage for engaging the toe end of the insole and the toe end of the last relatively to position the insole and the last lengthwise of the last, and means for drawing the upper into tight fitting relation to the last.

35 30. In a machine for use in assembling an upper on a last, a toe rest and a heel rest arranged to engage respectively the toe and heel portions of the bottom of an insole on a last having an upper assembled in loose relation thereon, said rests being relatively adjustable in directions heightwise and lengthwise of the last and being arranged to cooperate in supporting the last right side up, means for relatively positioning the insole and the last lengthwise of the last, side gages for engaging the opposite edges of the forepart of the insole and the opposite sides of the last relatively to position the insole and the last widthwise of the last, and means for drawing the upper into conforming relation to the last.

35 31. In a machine for assembling an upper in close fitting relation upon a last having an insole thereon, a toe rest for engaging the toe portion of the bottom of the insole to support the last, a heel rest for engaging the heel portion of the bottom of the insole to cooperate with said toe rest in supporting the last, an abutment on said toe rest arranged to engage the toe end of the last to prevent forward displacement of the latter relatively to said supporting means, a foredraw member for engaging the forepart of the upper, means for operating said member to draw the upper forwardly on the last, and means for adjusting the toe rest lengthwise of the last relatively to the foredraw member.

32. In an assembling machine, means for supporting a last having an upper and an insole arranged in loose relation thereon, means for aligning the edge of the insole with the edge of the

last bottom, and means for tightening the upper about the heel and forepart portions of the last and for adhesively securing it to the insole.

33. In an assembling machine, means for supporting a last having an upper and an insole arranged in loose relation thereon, gaging means for relatively positioning the last and the insole both widthwise and lengthwise of the last, and means for drawing the upper into tight fitting relation to the heel and forepart portions of the last.

34. In a machine for use in assembling an upper and a last, a rest for supporting a last by engagement with an insole on the last, means for positioning the insole lengthwise relatively to the last and for holding the last against forward displacement, a foredraw member, and means for moving the foredraw member in one direction to engage the upper and cooperate with said rest in clamping the last and in another direction to draw the upper forwardly to tighten it about the heel of the last.

35. In a machine for use in assembling an upper and a last, a toe rest for supporting a last by engagement with the toe of an insole on the last, a gage on the toe rest arranged to extend between the last and an upper loosely mounted on the last to position the insole relatively to the last and to hold the last against forward displacement, a foredraw member movable by an operator into position for cooperation with the toe rest to clamp the last, and power means for moving the foredraw member to draw the upper forwardly on the last.

36. In a machine for use in assembling an upper and a last, means for supporting a last having an upper loosely mounted thereon, a lever having means for frictionally engaging the upper in a location opposite the top of the forepart of the last, a yieldable support to which said lever is fulcrumed, and means constructed and arranged to swing said lever about its fulcrum to engage it with the upper and thereafter to move said fulcrum relatively to the last to cause said member to tighten the upper.

37. In a machine for securing in assembled relation an upper having a cemented margin and an insole arranged in loose relation on a last, work supporting means, means for drawing the upper forwardly on the last, wipers arranged at opposite sides of the forepart of the last, means for operating said wipers to tension the upper widthwise of the forepart of the last to conform it to the curvature of the last and to hold the upper in conformed condition, and means for laying the cemented margin of the upper inwardly over the bottom of the insole while the upper is held by said wipers.

38. In a machine for securing in assembled relation an upper having a cemented margin and an insole arranged in loose relation on a last, work supporting means, means for engaging the forepart of the upper and drawing it forwardly on the last, two wiper arms arranged one at either side of the last, wipers carried by said arms for frictionally engaging the upper, means for urging said wiper arms toward each other, means normally opposing inward movements of said wiper arms to hold said wipers out of engagement with the upper, and means for moving said wiper arms in directions to disengage them from said last-named means and to operate said wipers to tighten the upper.

39. In a machine for securing in assembled relation an upper having a cemented margin

and an insole arranged in loose relation on a last, a rest for supporting the work by engagement with the insole, wipers for engaging the upper at opposite sides of the forepart and for wiping it downwardly to conform it to the transverse curvature of the forepart of the last, levers mounted below said work rest and having upwardly extending arms arranged to swing toward each other, overlaying members carried by said arms arranged to yield downwardly, and means for operating said levers to move said overlaying members into yielding engagement with the cemented margins of the upper to press the latter against the bottom of the insole.

40. In a machine for securing in assembled relation an upper having a cemented margin and

an insole arranged in loose relation on a last, a work support, gages arranged to extend between the upper and the sides of the last for locating the forepart of the insole relatively to the last, means for drawing the upper forwardly on the last, wipers movable toward said gages for conforming the forepart of the upper to the transverse curvature of the last, overlaying members for yieldingly engaging the cemented margins of the upper, and means for retracting said gages to make way for said wipers and for moving said overlaying members toward each other to lay the margins of the upper inwardly over the bottom of the insole.

BERNHARDT JORGENSEN.

CERTIFICATE OF CORRECTION.

Patent No. 2,033,245.

March 10, 1936.

BERNHARDT JORGENSEN.

It is hereby certified that error appears in the printed specification of the above numbered patent requiring correction as follows: Page 6, first column, line 9, for "ar" read are; page 7, first column, line 15, claim 14, for "of" read on; and that the said Letters Patent should be read with these corrections therein that the same may conform to the record of the case in the Patent Office.

Signed and sealed this 12th day May, A. D. 1936.

Leslie Frazer

(Seal)

Acting Commissioner of Patents.
